UNITED STATES PATENT OFFICE.

FREDERICK HACHMANN, OF ST. LOUIS, MISSOURI, ASSIGNOR TO WILLIAM H. GREGG, OF ST. LOUIS, MISSOURI.

MANIFOLD SALES BOOK AND COVER THEREFOR.

1,421,461.

Specification of Letters Patent.

Patented July 4, 1922.

Application filed March 25, 1921. Serial No. 455,422.

To all whom it may concern:

Be it known that I, FREDERICK HACHMANN, a citizen of the United States, and resident of the city of St. Louis and State 5 of Missouri, have invented certain new and useful Improvements in Manifold Sales Books and Covers Therefor, of which the following is a specification, containing a full, clear, and exact description, reference 10 being had to the accompanying drawings, forming a part hereof.

My invention relates to improvements in manifold sales books and covers therefor, and has for its primary object a sales book 15 in which the original and duplicate sales tickets and a tissue copy are made simultaneously and in which the tissue sheet is already interposed between the original and duplicate. 20 A further object of my invention is to construct a manifold sales book in which the original and duplicate sales tickets are bound to a back, and which has the tissue sheets bound to the same back and interposed between the original and duplicate, so as to form virtually a single book which is adapted to be held at both ends within my improved cover. 25

A still further object is to construct a 30 cover for sales books in which the sales book is held by spring clamps, one of the covers having an extra plate hinged thereto, which serves both as a carrier for the total sales slip and a protecting cover for the used tissue sheets.

In the drawings—

Fig. 1 is a side elevation of my complete device;

Fig. 2 is a top plan view;

Fig. 3 is a top plan view with the front cover and protecting plate removed;

Fig. 4 is a top plan view of the book as opened, showing some of the tissue sheets inserted under the protecting cover;

Fig. 5 is a plan view of one form of sales ticket showing the manner of preparing the same for the reception of the tissue sheet;

Fig. 6 is a fragmental plan view of one of the tissue sheets employed;

Fig. 7 is a top plan view of my preferred form of manifold sales book;

Fig. 8 is an enlarged side elevation showing the manner of folding the original and duplicate sheets and inserting the tissue 55 sheet;

Fig. 9 is a perspective fragmental view showing the edge of the tissue projecting from between the original and duplicate;

Fig. 10 is a plan view of a modified form 60 of sales book;

Fig. 11 is an enlarged side elevation of the same; and

Fig. 12 is a fragmental elevation of the tissue sheet and original showing the manner of attaching the two together. 65

Fig. 13 is an enlarged side elevation of the stiff back, showing a number of original and duplicate tissue sheets and carbon sheet in their proper relation.

In the construction of my device I employ 70 a manifold book having the duplicate sheet 13, the original 14 and a tissue sheet 15. The duplicate sheet 13 has its end secured to a stiff back 16, this being preferably of cardboard. The duplicate and original 75 sheets are formed integral, and folded upon each other at a point indicated by the numeral 17. A portion of the fold is cut away, leaving a slot or slit through which the end 18 of the tissue sheet 15 projects. 80 This projecting end 18 is likewise secured to the back 16. Each sales ticket is made in the identical manner and placed one upon the other, that is, a duplicate, a tissue sheet and an original. In this manner the entire 85 book is built up, there being approximately fifty sets of slips to a book. At intervals between the sheets are placed sheets of carbon paper 19. This carbon paper is double-faced, and is adapted to be inserted between 90 the duplicate and the tissue sheet so that three copies will be made simultaneously.

After the book has been thus formed, it is secured within the cover, which consists of the back cover 20, which is provided along 95 each of its narrow edges with right-angular projections 21 and 22. These projections are formed into loops 23 and 24, through which are inserted the hinge wires 25 and 26. The back 22 is also provided with ribs 27, 100 which prevent the cover from scratching the table. Formed integral with the back and projecting upward at right angles are a series of teeth or projections 28 and 29, which are designed to contact and grip the back 16 of the sales book.

Hingedly secured to the wire 26 is a spring-actuated clamp 30, which has projecting teeth 31. These teeth are adapted to grip the upper duplicate slip and thus 110

hold the one end of the sales book within the cover. The clamp 30 is provided with loops 32, through which the hinge wire 26 passes.

5 Surrounding the hinge wire 26 are coil springs 33, having one end resting on the clamp 30 and the other end against the projection 22. These coil springs hold the clamp 30 tightly against the one end of the 10 sales book.

Formed on the projection 21 are loops 23, through which the hinge wire 25 passes, and surrounding this hinge wire are loops 35, which are formed integral with a spring- 15 actuated clamp 36. This clamp is constructed identical with the clamp 30, and is for the purpose of holding the tissue end of the book within the covers.

Hingedly secured to the pin or wire 25 by 20 means of the loops 37 is a top cover 38, which is also provided with ribs 39 to prevent it from scratching the furniture. The end of the cover 38 opposite the loops 37 is provided with loops 40 which are adapted 25 to receive a hinge wire 41, and secured to this hinge wire is a protecting plate 42, this plate being secured to the wire 41 by means of loops 43.

The free end of the plate 42 is provided 30 with an extension 44, which is adapted to be folded over the plate and form a pocket 45 for receiving one end of the total sales ticket 46. The cover 42 is also provided 35 with a flange 47 located between the loops 43. This flange is adapted to be folded over a strip of metal 48, forming a pocket 49 which receives the other end of the total sales ticket.

The protecting cover 42 is provided along 40 its remaining edges with the bead 50, this bead serving also to close the pockets 45 and 49 at their ends and prevent the sales ticket 46 from sliding out sideways.

The covers 20 and 38 are also provided 45 with beaded edges 51, which serve to stiffen the cover as well as eliminate sharp edges.

Referring to Fig. 5, the duplicate 52 and original 53 are folded one upon the other similar to the original and duplicate 14 and 50 13, but in this instance the fold 54 is cut away from both sides, leaving the two tickets joined together at their center portion. When the tickets are constructed in this manner the tissue sheet is provided with two 55 projections 55, which extend through the slots formed by the cut-away portion and through these projections the tissue sheets are secured.

In Figs. 10, 11 and 12 I have shown another modified form of sales ticket in which 60 I use the back 56, to one end of which is secured the duplicate sales ticket 57, and to the other end the tissue sheet 58. Attached to the free end of the tissue sheet 58 is the 65 original 59. This attaching is done by

means of a narrow strip of glue which holds the two strips together in such manner that the original can be readily detached therefrom.

In sales books as at present constructed 70 where a tissue copy is made, the tissue is either bound in a book which is attached separately to the cover and it is always necessary to insert a fresh tissue sheet when making out a sales ticket, or another form is 75 where the tissue sheet is glued to the original, but in this instance when a sales ticket is filled out, the tissue sheet has to be torn loose and placed in a separate pocket. This frequently results in the loss of tissue sheets, 80 as well as causing a lot of trouble in arranging the tickets when they reach the proper officer for checking up.

By the use of my device it is impossible to forget to make a tissue copy, as is frequently 85 the case where the tissue is in a separate book, and there is no possibility of the tissue sheets becoming lost or deranged, as they are secured to the back and being placed between the sales tickets when the 90 same are blocked they will run in sequence and consequently cannot get mixed up and require straightening after the book has been used and the tissues sent to the office.

My object in making Fig. 7 the preferred 95 form is that a great many stores require the original and duplicate to be sent to the cashier without being torn apart. In order to do this it is only necessary to pull back the original and grasp the duplicate, which can 100 readily be torn from the stub. This leaves the original and duplicate secured together at the folded portion 17 and when the two tickets reach the cashier, they can be readily torn apart.

Having fully described my invention, 105 what I claim is:

1. A manifold sales book, comprising a plurality of original and duplicate sales tickets integrally formed and folded so as 110 to lay upon each other, said tickets being partially separated along their folded edge, a tissue sheet located between each original and duplicate ticket, said tissue sheet having a portion projecting through the separation of the ticket, a back of relatively 115 stiff material, and means for attaching the duplicate tickets and tissue sheets to opposite edges of the back.

2. A device of the class described, comprising a back cover, having two up-turned edges, a series of upwardly projecting teeth formed integral therewith, and near the up-turned edges, loops formed on the up-turned edges, a top cover having loops formed 125 along two of its edges, a wire extending through said loops and through the loops of one of the up-turned portions of the back cover for hingedly connecting the same together, a wire extending through the loops 130

formed on the remaining portion of the back cover, a spring-actuated clamp secured to each of said wires, a protecting-plate having loops along one edge, a wire adapted to be inserted through the loops on one edge of the top cover and the loops on the plate for hingedly connecting the same together, a pocket formed along two edges of the protecting plate, said pocket adapted to receive a total sales ticket, ribs formed integral with the top and back cover, said ribs adapted to prevent scratching, a manifold sales book comprising a plurality of original and duplicate sales tickets and tissue sheets, a back to which the duplicate sales tickets and tissue sheets are secured, said manifold sales book inserted beneath the spring clamps and held within the covers.

3. A manifold sales book, comprising a plurality of original and duplicate sales tickets, a plurality of tissue sheets interposed between the original and duplicate tickets, said tissue sheets projecting beyond the edges of the original and duplicate tickets, a projection secured to one end of said duplicate tickets, and a back of relatively stiff material to which the projections of the duplicate tickets and of the tissue sheets are secured.

30 4. A device of the class described, comprising a back cover having two edges at right angles thereto, a plurality of loops formed along said edges, a spring-actuated clamp hingedly secured to each of said loops, a cover hingedly secured to one of said projections, a protecting-plate hingedly secured to said cover, pockets formed in said protecting-plate to receive a total sales ticket, ribs formed on the said covers to prevent scratching, and upwardly projecting teeth formed integral with the back cover and adjacent the up-turned ends.

5. A manifold sales book comprising a back, a plurality of duplicate sales tickets, having one end secured to the back, a plurality of tissue sheets having one end secured to said back, one of said tissue sheets arranged on the top of each of the duplicate sales tickets, an original sales ticket placed on top of each tissue sheet and so arranged as to prevent its shifting relative to the duplicate ticket and tissue sheet, a carbon sheet arranged between the duplicate sales ticket and tissue sheet, whereby three copies may be made simultaneously, said original and duplicate sales tickets being capable of being torn from the back and the tissue sheets remain in book form attached to the back, an auxiliary back for said book, a cover hinge to said back, a means for detachably securing said book to the auxiliary back.

6. A manifold sales book comprising a back, a plurality of original and duplicate sales tickets integrally formed and folded upon each other and arranged to be disconnected from said back, a tissue sheet located between each original and duplicate sales ticket, and projecting beyond the fold in said original and duplicate sales tickets, a carbon sheet secured to said back and arranged between the duplicate ticket and tissue sheet, means for attaching the tissue sheets to said back in book form, and an inter-locking connection between the original and duplicate sales tickets and said tissue sheets, whereby the accidental displacement of the tissue sheets is prevented, a metal cover for said book having a hinged front cover, and means for detachably securing said book within said cover.

In testimony whereof, I have signed my name to this specification.

FREDERICK HACHMANN.
